UNITED STATES PATENT OFFICE.

HUGH FLYNN, OF OLEAN, NEW YORK.

MEANS FOR UTILIZING THE POWER OF A RIVER.

No. 921,687.

Specification of Letters Patent.

Patented May 18, 1909.

Application filed July 16, 1908. Serial No. 443,781.

To all whom it may concern:

Be it known that I, HUGH FLYNN, a citizen of the United States, and a resident of Olean, in the county of Cattaraugus and State of New York, have invented certain new and useful Improvements in Means for Utilizing the Power of a River, of which the following is a specification.

It is a well known fact that large rivers possess great possibilities for the development of power for all kinds of uses and various plans have been devised for obtaining power therefrom. The greatest power is obtainable at a falls; but all plans for securing power there are objectionable because it means the destruction of at least some of the natural beauty of the falls. Besides the falls the next place for obtaining power is on the river above the falls and I have devised means for so utilizing the force of the river current above a falls that great power may be obtained without destroying any of the natural beauty of the river or falls and in such a way that the water used for the generation of the power is immediately returned to the river so that it flows in its fullest capacity over the falls as heretofore.

In the drawings forming a part of this application, Figure 1 is a plan view of a part of the Niagara river showing the application of my invention, Fig. 2 is an enlarged plan view of the entrance to the waterways, and Fig. 3 is an elevation partly in section of one of the waterways.

It is a geographical fact that islands are situated in the various rivers above falls and are of considerable size, and the river flows on each side of the islands in great volume and the upper end of the island meets with the full force of the current of the river which at this point is very great, being much greater than below the falls.

My invention contemplates the use of waterways extending over an island which will take water from the river at the upper end of the island and return it at the lower end and while passing through such waterways it will operate a power means such as water wheels from which power is derived.

By disposing these waterways along an island waterways of considerable length may be provided which will take water from the river only temporarily and will return it at the lower end of the island so that the river flows at the falls at its full capacity and nothing is done to take away any of the natural

beauty of the falls or river, or alter its natural course. These waterways may be provided in large numbers and by running them lengthwise of the island and the direction of flow of the water when it strikes the upper end of the island the greatest amount of force is derived therefrom. That is to say, no bends in the waterways, which would decrease the generating force of the current, are necessary.

I prefer to form the waterways by building concrete walls such as 2, 3, along the island 1, which, with the bottom 4, forms a passage-way for the water, running from shore to shore of the island and so disposed that the current will cause the water to pass rapidly therethrough. There may be provided any number of intermediate walls 5, to divide the whole into any number of separate waterways 6. At the upper ends of the walls 2 and 3 that is, near the upper shore of the island, I place piers 7 and 8, which diverge outwardly from the walls and tend to divert the water into the waterways.

In the waterways I provide means for generating power, such as water wheels 9 which are journaled in journals 10 on the walls of the waterways and they are positioned so that the blades 11 extend into the water in the waterways so that the flow of the water will revolve the water wheels and provide power which may be transmitted through the miter gears 12, 13, to shaft 14, and then distributed for use. The water wheels are placed in numbers successively along the length of the waterway so that the water during its passage therethrough will operate on a number of wheels and thus produce considerable force.

Where there are a number of water wheels placed successively as is shown there is a tendency of the water to form in eddies after each wheel which would interfere with the proper working of the device and to prevent this I employ projections 15, which project from the opposite walls of the waterway and preferably opposite each other, which converge so as to reduce the space for the passage of the water and are disposed so as to affect the water just before it contacts with the several wheels.

It will be apparent that with the arrangement here set forth a great deal of power may be obtained from the force of the current without in any way destroying the natural beauty of the falls or river as the water is

only temporarily taken from the river and is returned to continue over the falls.

Having described my invention what I claim is,

5 1. Means for utilizing the power of a river, comprising waterways disposed across an island situated in the river, said waterways communicating with the river and means adapted to be operated by the passage of the water through said waterways.

10 2. Means for utilizing the power of a river, comprising a waterway disposed across an island, opening at the upper end of the island and communicating with river below, said waterway being disposed substantially in the line of the current of the river as it strikes said waterway and power means adapted to

be operated by the flow of water through said waterway.

3. Power generating means comprising 20 means forming a waterway, a plurality of water wheels successively arranged along the waterway and adapted to be operated by the water in said waterway and converging projections disposed so as to deflect the water 25 near the water wheels by reducing the water passageway near the water wheels.

Signed at Olean, in the county of Cattaraugus and State of New York, this 10th day of July, 1908.

HUGH FLYNN.
